UNITED STATES PATENT OFFICE

168,747

CHAIN SAW

Arthur W. Mall, Flossmoor, Ill., assignor to Mall
Tool Company, Chicago, Ill., a corporation of
Illinois

Application February 25, 1952, Serial No. 18,654

Term of patent 14 years

(Cl. D93—4)

To all whom it may concern:

Be it known that I, Arthur W. Mall, a citizen of the United States, residing at Flossmoor, State of Illinois, have invented a new, original, and ornamental Design for a Chain Saw, of which the following is a specification, reference being had to the accompanying drawing, forming a part hereof.

Fig. 1 is a side perspective view of a chain saw showing my new design.

Fig. 2 is a side perspective view thereof, but taken from the side opposite to that shown in Fig. 1.

Fig. 3 is a rear end perspective view thereof.

I claim:

The ornamental design for a chain saw, as shown.

ARTHUR W. MALL.
